UNITED STATES PATENT OFFICE.

WRIGHT PRESTWICH AND ERNEST PRESTWICH, OF LAWRENCE, MASSACHUSETTS.

REMOVABLE HANDLE MECHANISM FOR BRUSHES OR BROOMS.

1,423,151.

Specification of Letters Patent. Patented July 18, 1922.

Application filed December 15, 1919. Serial No. 344,797.

To all whom it may concern:

Be it known that we, WRIGHT PRESTWICH and ERNEST PRESTWICH, citizens of the United States, and residents of Lawrence, county of Essex, State of Massachusetts, have invented an Improvement in Removable Handle Mechanisms for Brushes or Brooms, of which the following description, in connection with the accompanying drawing, is a specification, like characters on the drawing representing like parts.

This invention relates to improvements in removable handle mechanisms for brushes or brooms and the object thereof is to provide a handle mechanism which can be effectively attached to brushes of the usual commercial form and which can be readily removed when the brush is worn out and applied to another brush.

20 A further object of the invention is to provide a handle mechanism for brushes which can be applied to a brush of any width and effectively clamped thereupon.

25 A further object of the invention is to provide a handle mechanism for brushes in which an ordinary broom handle may be utilized.

30 Further objects and features of the invention will more fully appear from the following description and the accompanying drawings, and will be pointed out in the annexed claims.

35 The drawings illustrate our invention as applied to brushes such as floor brushes, but it will be understood that it may be used in connection with any type of brush, whether the brush is of stiff or soft fibres, or whether the brush has a flat or a curved back.

40 In the drawings:

Fig. 1 is a side elevation of a preferred form of removable handle mechanism as applied to a brush.

Fig. 2 is a plan view on line 2—2 Fig. 1.

45 Fig. 3 is a vertical sectional view on line 3—3 Fig. 2.

Fig. 4 is a vertical sectional view of a modified form of removable handle mechanism for brushes applied to a brush having a head presenting a curved upper surface.

50 Fig. 5 is a transverse sectional view through the end of the handle and handle holder in a plane located adjacent to the edge of the handle embracing strap, showing the

manner in which said strap is secured to the 55 handle and handle holder.

The invention is illustrated in Figs. 1, 2, and 3, as applied to a brush having a flat head 1 and provided with any usual type of broom straws, or bristles 2. The removable handle mechanism comprises a frame 3 having a back adapted to rest upon a portion of the head of the brush and provided with upwardly extending flanges 4 and 5. The base of the frame 3 may be of any size 65 or form and desirably is so constructed as to fit the back of the brush. Where it is to be used upon flat brushes, such as are illustrated in Figs. 1, 2, and 3, the back of the frame is flat or may be curved as illustrated 70 in Fig. 4. When the device is to be used with brushes having heads presenting a curved surface, the frame may be secured to the brush in any desirable manner. As illustrated in Figs. 1 and 2 gripping members are 75 provided which have parallel sections 6 and 7 seated within the flanges 4 and 5, respectively, of the frame. The gripping members are also provided with down-turned extensions 8 and 9 the ends of which are curved 80 to fit underneath the head of the brush. The sections 6 and 7 of the gripping members may be clamped to the frame in any desirable manner, but preferably are secured therein by the same means which 85 clamps the handle holder to the frame.

A preferred form of handle holder comprises a plate 10 having an angularly disposed offset end portion 11 formed to fit in between the flanges 4 and 5, and secured 90 therein by a screw 12 having an enlarged head 13 seated in a countersunk recess in the frame 3 and preferably having a square portion 14 extending upwardly between the sections 6 and 7 of the gripping members and 95 through an aperture in the portion 11 of the handle holder; a nut 15 preferably having wings 16 upon the screw serves to clamp the handle holder and the gripping members firmly upon the frame.

100 The handle holder may be provided with any suitable means by which a handle may be secured to it. A preferred device which is illustrated herein as particularly adapted to receive broom handles, comprises a flat strap 17 bent into a loop form, the ends 18 of the loop being passed through suitable slots in the holder 10 and bent upwardly

around the edges thereof so as to clamp the loop strap firmly upon the holder 10. A broom stick 19 or other handle may be secured in the loop 18 by screws 20, or any other suitable fasteners.

By reason of the construction above described the position of the frame 3 upon the top of the brush may be varied or adjusted in such a manner that pressure applied to the handle will operate the brush properly. The adjustability of the gripping members enables them to be used with brushes of different widths, so that the handle mechanism may be applied to a brush of any size, or any usual form. While the gripping members will usually retain the brush between them without assistance, the vertical portion may be secured to the brush by screws as illustrated in Fig. 2, these screws being removed, of course, when it is desired to detach the brush holding mechanism from one brush for the purpose of applying it to another.

A modified form of our invention is illustrated in Fig. 4 as applied to a brush 21 having a rounded head 22. In this construction the frame 23 is formed to fit the convex surface of the brush head and is provided at one side with an inturned edge 24 which enters beneath the head of the brush. The frame 23, like the frame 3, desirably is provided with upwardly extending flanges 25 to receive the handle holder there-between. The handle is in the form of a flat bar 26 having its end 27 curved to conform to the curvature of the frame 23, and to fit between the flanges 25 of said frame. It is also provided with a flat strap 28 to receive a broom handle 29, as described. The portion 27 of the holder may be clamped to the frame by a screw 30 extending through the inclined aperture in the brush which is usually provided to receive an ordinary handle; an anchor plate 31 being secured over said aperture and desirably provided with a prong 32 entering the wood of the head to prevent displacement of the plate 31. A winged nut 33 applied to the screw serves to clamp the holder firmly against the frame 23. By reason of this simple construction the handle mechanism may be readily attached to, and detached from, the heads of brushes of the usual type, so that the handle may be employed for different brushes.

This invention permits the removal of a worn brush from the handle and the replacement of another brush, or if brushes of different size and different texture are to be employed in different kinds of work the same handle may be applied to each of the various brushes, thereby avoiding the necessity of keeping a large number of handles on hand, and reducing the cost of a set of brushes when the same are sold in sets, with

a single handle instead of a handle for each brush.

It will be understood that the embodiments of the invention disclosed herein is of an illustrative character and is not restrictive and that various modifications in construction and arrangement of parts may be made within the spirit and scope of the following claims.

Having thus described our invention, what we claim as new and desire to secure by Letters Patent, is:

1. Removable handle mechanism for brushes comprising a frame having a back adapted to fit upon the head of the brush and provided with upwardly extending parallel flanges, gripping means to engage an edge of a brush, a handle holder having a member fitting between said flanges and provided with means to receive a handle and means for clamping said frame and handle holder to said brush head.

2. Removable handle mechanism for brushes comprising a frame having a back adapted to fit upon the head of the brush and provided with upwardly extending parallel flanges, gripping means to engage an edge of a brush, a handle holder having a member fitting between said flanges and provided with means to receive a handle and means for clamping said frame, handle holder and brush head together.

3. Removable handle mechanism for brushes, comprising a frame having a back adapted to fit upon the head of the brush, and provided with upwardly extending parallel flanges, gripping members adjustably positioned between said flanges, a handle holder having a member fitting between said flanges, and means operating to clamp said gripping members and said handle holder to said frame.

4. Removable handle mechanism for brushes, comprising a frame adapted to rest upon the head of the brush, and provided with upwardly extending parallel flanges, gripping means comprising parallel members slidably mounted between said flanges and having respectively down-turned ends adapted to grasp opposite edges of the brush head, a handle holder having a member fitting between said flanges, a screw seated in said frame extending upwardly between said gripping members and through said handle holder, and a nut on said screw operable to clamp said handle holder and said gripping members to said frame, and to retain the same in gripping engagement with the brush head.

In testimony whereof, we have signed our names to this specification.

WRIGHT PRESTWICH.
ERNEST PRESTWICH.
